DISPLAY RACK FOR TOOL HANDLES

Norman Link, Salem, Ind., assignor to 'O. P. Link Handle Company, Inc., Salem, Ind., a corporation of Indiana

Filed Dec. 19, 1957, Ser. No. 48,968

Term of patent 14 years

(Cl. D80—9)

Fig-1

Fig-2

Fig. 1 is a front perspective view of a display rack showing my new design;

Fig. 2 is a vertical sectional view thereof taken on line 2—2 of Fig. 1.

The broken line representation of tool handles in Fig. 1 is for illustrative purposes only.

I claim:

The ornamental design for a display rack for tool handles, as shown and described.
